(57) **CLAIM**

The ornamental design for a catheter handle, as shown and described.

DESCRIPTION

FIG. 1 is a perspective view of a catheter handle according to the present invention.

FIG. 2 is a first side, elevational view of the catheter handle for the catheter shown in FIG. 1.

FIG. 3 is a top side, elevational view of the catheter handle for the catheter shown in FIG. 1.

FIG. 4 is a bottom side, elevational view of the catheter handle for the catheter shown in FIG. 1.

FIG. 5 is a first end plan view of the catheter handle shown in FIG. 1; and,

FIG. 6 is a second end plan view of the catheter handle for the catheter shown in FIG. 1.

1 Claim, 6 Drawing Sheets

FIG. 1

FIG. 2

FIG. 3

FIG. 4

FIG. 5
